TYPE-WRITING ATTACHMENT FOR ADDING-MACHINES.

1,110,448.

Specification of Letters Patent. Patented Sept. 15, 1914.

Application filed January 16, 1911, Serial No. 602,785. Renewed October 9, 1911. Serial No. 653,757.

To all whom it may concern:

Be it known that I, FRED F. MAIN, a citizen of the United States, residing at Chicago, in the county of Cook and State of Illinois, 5 have invented new and useful Improvements in a Type-writing Attachment for Adding-Machines, of which the following is a specification.

My invention relates to a typewriting attachment for adding machines.

The object of my invention is to provide an attachment for the standard adding machines which shall give to them the advantages of a typewriter without in any way 15 interfering with the normal work of the adding machine.

My device is shown attached to the well known "Burroughs" adding machine, although I do not confine myself to the use of 20 this type of machine. Heretofore it has been necessary, whenever adding or computing is to be done in connection with written explanations, to use a typewriter, provided 25 with an adding attachment. The difficulty in this class of machines, when the work of the adding machine predominates, is that the typewriter is not so rapid for listing numbers as the adding machine.

My device is especially adapted to work 30 where the listing of numbers predominates and for this reason the adding machine is left in its normal working condition with the typewriter attachment for the occasional 35 word of explanation. Heretofore in such machines the attachment has been made either as a separate machine, adapted to write upon the same platen as the adding machine or the adding machine and typewriter have been built as one machine in 40 which the adding machine is controlled by the typewriter keys. With my device I employ two sets of keys. The typewriter attachment is applied to the adding machine, but its action is entirely independent of the 45 adding machine. So also is the adding machine entirely independent of the typewriter attachment so far as the work is concerned, although the typewriting attachment is fastened securely to the adding machine.

50 In the class embodying the separate machine as a typewriter, which writes upon the same platen, the position of the keys of the typewriter has made its operation very

difficult. With my device I place the typewriter keys between the operator and the adding machine keys so that he may reach the typewriter keys with least effort, since they are nearer to him than the adding machine keys, nor does this position of the typewriter keys prevent the operator from sitting at or standing as close to the adding machine as he does sit or stand naturally in the work on the adding machine when no typewriter attachment is applied to it. I arrange the type bars so as to print upon the platen when the platen is pushed back, as it now moves on its pivot to permit the operator to see the printing line. This throws the printing line at nearly the top position of the platen so that the type bars 70 of the typewriting attachment may write in the same line as the adding machine.

One of the principal features of my device is the connection between the working parts of the adding machine and the platen 75 of the adding machine, so that the return of the handle of the adding machine shall always correctly place the platen in position for the type of the writing attachment, and at the same time when a number is to be 80 recorded in the adding machine, the forward movement of the handle or other oscillating parts of the adding machine shall move it to the extreme forward position, that is, the printing position of the adding 85 machine. The platen will receive the impression of the adding machine type, and the return of the handle or of the adding machine parts to their normal position shall again return the platen to the printing position for the writing attachment. In this way I prevent any possibility of recording on the adding machine with the platen out of position so as to prevent the adding machine type from recording on the platen as 90 I also make it impossible for the typewriter to be operated without having the platen in 95 position for the writing attachment.

To these and other ends the invention consists in a typewriting attachment for 100 adding machines wherein the type bars are located near the printing mechanism of the adding machine and operated by typewriter keys located at the front of the adding machine. The invention further consists in a 105 combined adding and typewriting machine

having a platen in common with the printing mechanism of both the adding machine and the typewriter, and mechanism operatively connected with the operating crank 5 of the adding machine or some other movable mechanism thereof, whereby the platen is shifted into printing position relative to the adding machine printing mechanism or the typewriter printing mechanism.

10 In the drawings furnished herewith:— Figure 1 is a side elevation of the "Burroughs" adding machine, showing my invention applied to it, Fig. 2 is a plan of a fragment of the same, Fig. 3 is a detail front view of the type bar mechanism, certain parts of the machine being cut away on the line 3—3 Fig. 2, Fig. 4 is a detail cross section taken on line 4—4, Fig. 2 and Fig. 5 are fragmental side elevations 15 of the type bar mechanism and its support. Fig. 6 is an elevation showing the platen swung forwardly out of typewriting position into position for receiving an impression from the adding machine. Fig. 7 is a plan of the machine. The typewriter keys are arranged at the sides of the machine; and it will be understood that the type bars at one side are duplicated at the other side of the machine, as in the Oliver 20 typewriter. The connections extend along the sides of the machine rearwardly from the keys to the type bars.

In the drawings, an adding machine known as the "Burroughs" machine 10, is 35 illustrated, said machine being provided with the usual keys 11, that are depressed to set the mechanism, in adding or computing. The machine contains a support 14, for the carriage 15, said carriage being slidably mounted upon the support 14, as usual. The carriage has an oscillatory platen supporting frame 15^a, which is fulcrumed upon the remainder of the carriage at 16, whereby it may be moved into either of two printing 40 positions. The frame 15^a, of said carriage supports the platen 12, in suitable bearings whereby the platen may rotate therein.

Under normal conditions the platen lies 45 in position to be printed upon by the typewriting attachment, and mechanism has been provided for causing said platen to assume the position wherein the printing mechanism of the adding machine may print upon the platen. A simple means for 50 accomplishing this result comprises a connection between the platen or its support and some part of the operating mechanism of the adding machine, as for instance the operating crank 17, whereby when said 55 crank is drawn forward, to record in the adding machine and print, the platen is drawn forward into printing position relative to the printing mechanism of the adding machine.

60 65 As shown in the drawings a link 20, is

employed between the platen supporting frame 15^a, and the crank 17, one end of the link slidingly connecting with a rod 22, carried by the frame and extending parallel with the platen 12, the other end of the link being pivotally connected with the crank 17, at such a point in its length, as at 21, that the platen will be moved to the proper position whenever the crank 17, is moved through its arc of movement. The crank 70 17, is fastened upon a shaft 18, and bears a handle 19, by means of which it may be actuated.

Above the carriage and platen are located the type bars of the typewriting mechanism, 80 and they are supported in such manner that when the type bars are swung down, the type strike upon the upper side of the platen. The typewriting mechanism employed, for the purpose of illustration, is substantially 85 that of the "Oliver" typewriter, although any other suitable mechanism may of course be substituted in its place. The type bar frame 23, is supported from the frame 10^a, of the adding machine as by a bracket 23^a, 90 which is bolted or otherwise secured to the adding machine frame and the type bars 24, are pivotally sustained in said type bar frame in the usual manner.

The typewriter keys 29, are located at the 95 front end of the machine and are operatively connected with the type bars 24, in such manner that the said type bars are swung down when the keys are depressed. One form of connection is shown in the drawings 100 28, and will be seen to comprise rock shafts 28,—one for each type key—journaled in bearings 30, secured to the side of the adding machine, each rock shaft having a crank 28^a, engaging with the typewriter key 29, 105 and a crank 27, connected with a type bar, as for instance by a link 25.

Each type bar is shown as formed with a lug 26, near its lower end, to which the link 25, is pivotally connected, said link extending laterally toward the side of the machine and connecting with the free end of the crank 27, of one rock shaft.

110 Springs 29^a, may be employed to return the typewriter keys and type bars to normal 115 position, said springs being shown as connecting the lower ends of the type keys with the frame 29^b, in which the type keys are mounted and guided. It is obvious that this particular construction and arrangement of 120 the type bar operating mechanism is not essential to the invention broadly considered, as there may be many forms of connections for operatively connecting the typewriter keys with the type bars.

125 In the operation of the adding machine, the usual conditions prevail, that is, the keys 11, are pressed in such a way as to represent the digits of the number to be recorded, when the crank 17, is pulled to the 130

forward position by means of the handle 19, as shown in the dotted lines (Fig. 1) and in this way the number is both recorded in the counter of the adding machine and 5 printed upon the platen 12, which is brought to the printing position by means of connection 20. On the return of the handle, the platen is forced to its backward position whereby the printing line of the adding machine is caused to register with the printing line of the typewriter, so that in case any 10 explanation or dates or numbers, not to be computed, be written, the type bars will print upon the platen as in the usual way 15 with a typewriter, since the platen now becomes the typewriter platen. The carriage, which combines the functions of both adding machine and typewriter, preserves the movements of the adding machine— 20 that is to say the adding machine carriage may be moved from right to left or the reverse or the platen may be moved back in order to bring to view the printing line, and said carriage, has added to 25 it the usual typewriter escapement and tabulating mechanism (not shown) since I make no claim for any specific escapement or tabulating mechanism. Should a word or more of explanation or a name be required in 30 the record, the same is written by using keys 29, the same as keys are used upon any typewriter when the type bars 24, by means of the rock shafts 28, will be driven to the printing line as in the usual manner on any 35 typewriter.

I show in the drawings the particular form of type bar mechanism employed on the "Oliver" typewriter, but I do not confine myself to this particular construction 40 since the essence of my invention consists in the position of the typewriter keys with relation to the adding machine keys and the novel means by which the typewriter bars are caused to operate together with the 45 movement of the platen, so that either machine may work with the same freedom as though it were not connected to the other, and at the same time the work of the two may be combined in such a way as to do all 50 of the work or any of the work which may now be performed by both machines acting independently in succession upon the same sheet. The importance of this work of the two machines in conjunction with each other 55 can hardly be realized as it not only saves the time and labor of printing upon the same sheet in one machine and then transferring it to another, but it avoids the greater disadvantage of the source of error 60 which exists where explanations are to be written for items already listed, or the reverse.

I am aware that various alterations and modifications of this device are possible 65 without departing from the spirit of my in-

vention, and I do not therefore desire to limit myself to the exact form of construction shown and described.

I claim as new and desire to secure by Letters Patent:

1. The combination with an adding machine having an operating shaft, of a typewriting machine and a platen common to the printing mechanism of said adding machine and typewriting machine, said platen 75 being operatively connected to said operating shaft of the adding machine, whereby it is brought into printing position relative to either machine by the movements of said shaft.

2. The combination with an adding machine having a rocking element, of a typewriter having an oscillatory platen common to the printing mechanism of said adding machine and typewriter, said platen being operatively connected with said rocking element of said adding machine, whereby it is moved into printing position relatively to either machine by the movement of said rocking element.

3. The combination with an adding machine, its operating shaft, and a typewriting machine, of a movable carriage having a platen common to the printing mechanism of said adding machine and typewriting machine, and operative connections between said platen and said operating shaft of the adding machine capable of moving said platen into printing position relative to either machine when said shaft is actuated 100 through its arc of movement.

4. The combination with an adding machine, its operating crank, and a typewriting machine, of a movable carriage having a platen common to the printing mechanism 105 of both machines, and a link slidably connected to said carriage and actuated by said operating crank of the adding machine, the movement of said link from one position to another being arranged to bring the platen 110 into printing position relative to either machine.

5. The combination with an adding machine, its operating shaft, and a typewriting machine, of a traveling carriage, and 115 a platen common to the printing mechanism of both machines said platen being carried by the carriage, and operatively connected with said shaft of the adding machine, whereby it may be moved into the printing 120 position for either machine.

6. The combination of an adding machine and the operating shaft thereof, a typewriter, a traveling carriage having an oscillatory frame, a platen, common to the printing mechanism of both machines, journaled upon said frame, and a link slidably connected to a longitudinal member of said frame and actuated by said operating shaft 125 of the adding machine, whereby said platen 130

- is brought into printing position relative to either machine by the action of said operating shaft.
7. The combination with an adding machine, and a typewriting machine associated therewith, of an oscillatory frame, a platen, common to both machines, journaled upon said frame and normally held in printing position with respect to the printing mechanism of the typewriter, and a link operatively connected to said oscillatory frame and extending to the operating crank of the adding machine, whereby said platen may be moved into printing position with respect 10 to the printing mechanism of the adding machine when said operating crank is pulled forward to record and print with the adding machine.
8. The combination with an adding machine, of typewriting mechanism having type bars supported on its rear end, a platen common to the printing mechanism of the adding machine and typewriting mechanism, said typewriting mechanism having 20 type keys located at the front of the adding machine, and rock shafts supported on the sides of the adding machine and operatively connecting the type keys with the type bars of the typewriting mechanism.
9. The combination with an adding machine, of typewriting mechanism having horizontally pivoted type bars located at the rear end of the adding machine, a link pivotally connected to each type bar, a rock 25 shaft for each type bar journaled on the side of the adding machine, and extending to the front thereof, each rock shaft having a crank attached to one link, and type keys located at the front of the adding machine 30 for rocking said rock shafts, and a platen common to the printing mechanism of the adding machine and the typewriting mechanism.
10. The combination with an adding machine having a set of keys and a platen, of a set of alphabet keys, and a set of type bars operable by said alphabet keys and mounted to write upon said platen: means being provided to shift the platen from adding position 35 to typewriting position; one set of keys being behind the other, and both sets between the platen and the operator.
11. The combination with an adding machine having a set of keys and a platen, of a set of alphabet keys, and a set of type bars operable by said alphabet keys and mounted to write upon said platen: means being provided to shift the platen from adding position to typewriting position; said alphabet 40 keys being in front of the adding machine keys and said type bars being behind said adding machine keys, and connections extending from said alphabet keys to said type bars.
12. The combination with an adding ma-
- chine having a set of keys and a platen, of a set of alphabet keys, a set of type bars operable by said alphabet keys and mounted to write upon said platen; means being provided to shift the platen from adding position to typewriting position; said alphabet keys being in front of the adding machine keys and said type bars being behind said adding machine keys, and connections extending from said alphabet keys to said type bars; said connections including devices extending from front to rear alongside of the adding machine.
13. The combination with an adding machine having a platen, of typewriting mechanism to write upon said platen; the platen being normally in position to receive impressions from the type bars; said adding machine having a general operator, and a connection from said general operator to 80 said platen to shift the latter to position to receive impressions from the adding machine types.
14. The combination with an adding machine having a platen, of typewriting mechanism to write upon said platen; the platen being normally in position to receive impressions from the type bars; said adding machine having a general operator, and a connection from said general operator to 85 said platen to shift the latter to position to receive impressions from the adding machine types.
15. The combination with an adding machine having a set of keys, a general operator handle and a platen, of a set of alphabet or typewriting keys, a set of type bars operable by said alphabet keys and mounted to 90 write upon said platen, and a connection from said general operator handle to said platen to return the platen to typewriting position after receiving the impressions of the adding machine types.
16. The combination of an adding machine, a typewriting mechanism having a platen in common with the printing mechanism of the adding machine, said adding machine having an operating crank or device, and mechanism operatively connected with said operating crank, whereby the platen is shifted into printing position relatively to each other the adding machine or the typewriter printing mechanism.
17. The combination of an adding machine, a typewriting mechanism having a platen in common with the printing mechanism of the adding machine, said adding machine having an operating crank or device, and mechanism operatively connected with said operating crank, whereby the platen is shifted into printing position relatively to either the adding machine or the typewriter printing mechanism, the link 100 extending 110
- 115
- 120
- 125
- 130

from said operating crank to the platen supporting frame.

18. The combination with an adding machine, of a platen for said adding machine arranged to carry a work-sheet to be written on by the printing mechanism of said adding machine and means for moving said platen bodily and automatically between each printing action to a position to bring 10 the line of writing visible to the operator of the machine.

19. The combination with an adding machine having printing mechanism, of a platen coöperating with said printing mechanism, and automatic means for swinging 15 said platen bodily to a position to expose the matter just printed between each operation of said adding machine.

20. The combination with a typewriting

machine, of a computing machine, said typewriting machine and said computing machine each having printing mechanism, a platen common to both said typewriting machine and said computing machine and alternately coöperable with either, and means 25 to cause said platen to coöperate normally with the printing mechanism of said typewriting machine and to coöperate solely with the printing mechanism of said computing machine when registering in said 30 computing machine.

In witness whereof, I have hereunto signed my name, at Chicago, Cook county, Illinois, this 13th day of January, 1911.

FRED F. MAIN.
